United States Patent Office

Des. 208,527
Patented Sept. 12, 1967

208,527

COMBINED APRON AND GLOVES

Walter M. Greeng, 4605 W. Beltline Highway,
Madison, Wis. 53711

Filed July 5, 1966, Ser. No. 2,948

Term of patent 14 years

(Cl. D2—27)

FIG. 1

FIG. 2

I claim:

The ornamental design for a combined apron and gloves, as shown.
